UNITED STATES PATENT OFFICE.

FREDERICK E. HEINIG AND SAMUEL LEIDIGH, OF LOUISVILLE, KENTUCKY.

CORK-RETAINER.

SPECIFICATION forming part of Letters Patent No. 378,007, dated February 14, 1888.

Application filed December 27, 1887. Serial No. 259,074. (No model.)

To all whom it may concern:

Be it known that we, FREDERICK E. HEINIG and SAMUEL LEIDIGH, citizens of the United States, residing at Louisville, in the county of 5 Jefferson and State of Kentucky, have invented certain new and useful Improvements in Cork-Retainers for Bottles; and we do hereby declare the following to be a full, clear, and exact description of the invention, such as to will enable others skilled in the art to which it appertains to make and use the same.

This invention relates to that class of cork-retainers for bottles which retainers pass over the cork and down around the neck of the bottle to hold the cork in the bottle against the pressure of gas contained in the bottle; and its object is to produce a complete retainer in one piece at a single punching from sheet material—such, for example, as tin—and to 20 shape it so that one portion, called a “cap,” may rest flatly over the top of a cork in a bottle, while other portions rest vertically against the sides of the head of the bottle, and yet another portion surrounds the neck of the bottle beneath the head, having but one pair of ends to be fastened together.

To this end the invention consists in a cork-retainer for bottles comprising in one piece a cap, a neck-band, and two diagonally-crimped 30 side straps joining the said band and cap, as hereinafter described and claimed, reference being had to the accompanying drawings, in which—

Figure I represents the blank form of our 35 retainer as it is made by punching from sheet metal. Fig. II is a side elevation of the same with the band half bent. Fig. III is a perspective view of the same after the headstalls are crimped. Fig. IV is a perspective view 40 of the same with the crimps flattened down all ready to be applied to a bottle, and Fig. V represents our retainer in service on the head of a bottle.

5 represents the cap, which we prefer to 45 make of a circular form suitable to rest on top of a cork.

6 represents the band, which is of suitable length to pass around the neck of a bottle beneath the head. This band may have any 50 suitable fastening to keep its ends together when around the neck of the bottle. The simplest fastening which we now think of is

represented by the tongue 7 at one end of the band and the eye 8 at the other end adapted to receive the tongue, the latter to be bent 55 over back when inserted to keep it in place.

9 represents the side straps, which connect the sides of the cap with the band. The side straps rise vertically from the edge of the band at a distance apart equal to half the circumference of the neck of the bottle, and at a point, 10, each makes a right-angular offset toward the other and joins the cap at its opposite edges. Now the band is to be bent to the semicircle of the bottle's neck, as in Fig. 60 II. Then by making a diagonal crimp or fold at the lines 11 the cap will be turned to its upright position, and ears formed by the crimping will project, as at 12, Fig. III. Now press 65 these ears flat down, as in Fig. IV, and the retainer is ready for use; and its method of application to a bottle is apparent, it being only necessary to place the cap portion on a cork, then put that into a bottle under a presser, as 70 usual in bottling aerated or gaseous fluids, and then pass the tongue 7 through the eye 8 and bend it back, when the cork will be securely 75 retained.

In folding the crimped ears 12 down against the face of the side strap the fold may be made 80 exactly at the base of the crimp or above or below it, so that a little variation in the length of the side strap may be made to fit bottles with heads of different heights. A variation of one-eighth of an inch is enough to meet any 85 irregularity in bottles of a given size. By means of our diagonal crimps in the side straps we tip the cap from its normal plane, which is the plane of the unbent band, to a plane at right angles therewith and parallel with the 90 plane of the circle of the band when bent, thus avoiding the necessity of two openings in the band and two pairs of ends to be joined. While we now suppose that tin is the most economical material for making our retainers, 95 any other suitable sheet metal or material may be used. It is not necessary that the cross portion comprising the cap should be of circular form midway. The cap may be lozenge-shaped, or even a mere straight-edged cross-strip parallel with the band. The cap may be 100 perforated, as shown in Fig. IV, for the admission of a goose-neck pipe in some styles of bottle-filling.

Having thus fully described our invention, what we desire to protect by Letters Patent is the following:

1. In a bottle-cork retainer, a sheet-metal blank comprising in one piece a band adapted to encircle the neck of a bottle and having one pair of ends adapted to be secured together, a cap to cross over the cork in a bottle, and side straps permanently connecting two opposite edges of the cap with one edge of the band, substantially as shown and described.
2. A blank for a bottle-cork retainer, comprising in one piece a band, a cap located at a little distance from one edge thereof, and side straps each having a side offset and connecting the cap with the band, substantially as shown and described.
3. A bottle-cork retainer comprising in one piece a band to encircle the neck of a bottle, a cap to cross over a cork in the bottle, and diagonally-crimped side portions joining the

cap with the band, substantially as shown and described.

4. A blank for a bottle-cork retainer having a band, a cap portion, and side portions with angular offsets and adapted to be crimped diagonally at the angle of the offset, substantially as shown and described.

5. In a bottle-cork retainer, side straps formed with angular offsets and crimped diagonally at the angles and the crimp folded down against the strap to bring the two portions of the strap into line, substantially as shown and described.

In testimony whereof we affix our signatures in presence of two witnesses.

FREDERICK E. HEINIG.
SAMUEL LEIDIGH.
